UNITED STATES PATENT OFFICE.

HENRY A. W. SMITH, OF CHATHAM, VIRGINIA, ASSIGNOR OF ONE-HALF TO EDWIN S. REID, OF CHATHAM, VIRGINIA.

RERAILER.

1,305,625.

Specification of Letters Patent.

Patented June 3, 1919.

Application filed November 29, 1918. Serial No. 264,647.

To all whom it may concern:

Be it known that I, HENRY A. W. SMITH, a citizen of the United States, residing at Chatham, in the county of Pittsylvania and State of Virginia, have invented a new and useful Rerailer, of which the following is a specification.

The device forming the subject matter of this application is adapted to be used for replacing the wheels of a derailed car upon the tracks, and one object of the invention is to provide novel means whereby the re-railing blocks may be held securely to the rails and have a firm bearing thereon, it being possible to attach the blocks to the rails at any points along the rails. It is within the province of the disclosure to improve generally and to enhance the utility of devices of that sort to which the invention appertains. Within the scope of what is claimed, changes may be wrought by a mechanic, without departing from the spirit of the invention.

In the drawings:—Figure 1 is a top plan; Fig. 2 is a section on the line 2—2 of Fig. 1; Fig. 3 is an elevation showing the inner side of one block.

In carrying out the invention there is provided a block 1 having a longitudinally convexed upper surface 2 and including a transversely slanting surface 3, the block being cut away upon its inner edge at its ends, as shown at 4, and being cut away upon its inner edge intermediate its ends as indicated at 5, to form a pair of laterally extended lugs 6 adapted to abut against the web 7 of a rail, there being a recess 8 in the inner edge of the block, between the lugs 6, for the reception of the flange 9 of the rail. For the sake of lightness, the block 1 may have an internal cavity 10. In the outer edge of the block 1 there is a plurality of seats 11 extended longitudinally of the block, the seats being disposed as closely together as desired.

The invention includes a pair of like rail clamps, each comprising a base 12 having an overhanging hook 14 at one end, and provided at its other end with an upstanding arm 15 having a boss 16 into which a screw 17 is threaded. The base 12 of the rail clamp extends beneath the block 1 and beneath the flange 9 of the rail, the hook 14 engaging one edge of the rail base. The inner end of the screw 17 is engaged in any

one of the seats 11 and thus the lugs 6 are pressed at their ends against the web 7 of the rail, the lugs being supported on the base flange 9 of the rail, to aid in supporting the block 1 and to prevent the block from 60 tilting.

Since the invention includes the rail clamps above mentioned, the block may be mounted on the rail at any desired place longitudinally of the rail. Further, there 65 is a distinct advantage in having the screws 17 engage at their inner ends with the block 1, instead of with the rail. First, owing to the construction above mentioned, the screw 17 may be made relatively short and it will, 70 therefore, possess the necessary strength. Again, it is unnecessary to mount on the inner end of the screw, a shoe or spacer of the kind used when the screw co-operates at its inner end with the rail, instead of with the 75 block. Especial attention is directed to this feature, in comparing the structures claimed with the prior art.

The invention includes a block 1^a having many of the features of the block 1 and including parts having the functions of corresponding parts in the block 1. Those parts of the block 1^a which are represented by similar parts in the block 1 are designated by numerals previously used, with the 80 suffix "a." The block 1 has transversely slanting portions 18 on its upper surface at its ends, and, between the lugs 6 there is a relatively long straight surface 19 adapted to bear against the edge of the ball of the 90 rail. The block 1^a has a central upstanding part 20, of triangular form and has an intermediate lug 21 coacting with the ball of the rail, the transversely slanting surface 3^a being located on this lug, the surface 3^a 95 merging into the inner edge surfaces 22 of the part 20, which slant transversely.

The general operation of a device of the kind described is well understood by those skilled in the art, and a glance at Fig. 1 will 100 render the operation evident, and the functions of the wheel-engaging parts of the blocks clear.

I claim:—

A device of the class described comprising 105 a block having a longitudinally convexed upper surface and including a transversely slanting surface, the block being provided on its outer side with longitudinally spaced seats, and having, upon its inner side, later- 110

ally projecting rail-engaging lugs spaced apart; a clamp extended beneath the block and provided at one end with a rail-engaging hook, the clamp being supplied, at its 5 opposite end, with an arm; and a screw-threaded into the arm and adapted to be engaged, directly, at its inner end, in any of the seats.

In testimony that I claim the foregoing as my own, I have hereto affixed my signature in the presence of two witnesses.

HENRY A. W. SMITH.
